United States Patent Office

Des. 210,929
Patented May 7, 1968

210,929

BRUSH HANDLE OR SIMILAR ARTICLE

Robert F. Mulvaney, Jr., 1480 Creekside Drive,
Walnut Creek, Calif. 94596

Filed Sept. 1, 1967, Ser. No. 8,466

Term of patent 14 years

(Cl. D4—38)

FIG_1

FIG_2

FIG_3

FIG_4

FIG_5

FIG_6

FIG. 7

FIG. 8

FIG. 1 is a top plan view of a brush handle or similar article showing my new design;

FIG. 2 is a side elevational view thereof;

FIG. 3 is a bottom plan view thereof;

FIG. 4 is an end elevational view thereof taken from the left of FIG. 2 shown in closed operating position;

FIG. 5 is an end elevational view thereof, taken from the left of FIG. 2 shown in open non-operating position;

FIG. 6 is a fragmentary cross-sectional view thereof, taken along the line 6—6 of FIG. 2;

FIG. 7 is an elevational view thereof taken from the right of FIG. 2; and

FIG. 8 is an end elevational view of the side opposite to that shown in FIG. 2.

The broken lines shown on the drawings are for illustrative purposes only.

I claim:

The ornamental design for a brush handle or similar article, as shown and described.
